ROTARY BELL

Eric Moard, East Hampton, Conn., assignor to
 Bevin Bros. Mfg. Co., East Hampton, Conn., a
 corporation of Connecticut

Application May 24, 1947, Serial No. 750,287

5 Claims. (Cl. 116—154)

1

This invention relates to rotary bells and more particularly to bicycle bells which are adapted to be rung by manual rotation of the bell member.

An object of this invention is to provide an improved rotary bell which may be readily operated with the hand and which is economical to produce and highly efficient in its operation.

A further object of the invention is to provide a bell which is adapted to operate with a two-tone sound upon the rotation of a single bell member.

Further objects and advantages of this invention will be more clearly understood from the following description and from the accompanying drawings in which:

Fig. 1 is an end view of a bell embodying my invention on line 1—1 of Fig. 2.

Fig. 2 is a side view, partly in central vertical section, illustrating my invention as embodied in a two-tone bell.

Fig. 3 is an end view in vertical section on line 3—3 of Fig. 2.

Fig. 4 is a side view, partly in central vertical section, of a bell showing a modified form of my invention.

Fig. 5 is a sectional end view thereof on line 5—5 of Fig. 4.

As illustrated in the drawings, my improved bell comprises a supporting plate 5 having rigidly mounted thereon a supporting shaft 6 which extends through said supporting plate and has an enlarged portion 7 which abuts the supporting plate. A squared section 8 fits through a square opening in the supporting plate and prevents rotation of the shaft.

An auxiliary supporting plate 9 is secured to the supporting plate 5 and spaced therefrom to provide a bearing of substantial width which receives the square portion 8 and rigidly supports the shaft 6 perpendicularly to the supporting plate 5. The said shaft may be fastened in position by swaging the edges of the squared section 8 against the outer surface of the auxiliary supporting plate 9 to thereby secure the plates 5 and 9 between the swaged portions and the shoulder provided by the enlargement 7.

As clearly illustrated in Fig. 2, a bell member 10 is threaded to the extension 6—a of the shaft 6 by means of an internal tubular hub 11 which rigidly secures the bell member 10 to the shaft.

A second bell member 12 is rotatably mounted upon the shaft 6 by means of an internal tubular hub 13 and is retained thereon by a snap ring 14. A cam 15, preferably having three projections 16, is rigidly secured to the hub member 13 to rotate therewith.

2

A hammer 17 is carried on a spring arm 18 which extends from a lever 19 and rests against the stop member 18—a. The said lever 19 is pivotally mounted on a stud 20, which extends from the plate 5 into the bell member 10, and is provided with a stud 21 which projects through a slot 22 in the supporting plate 5 to the opposite side of said plate to engage the cam 15; the said lever 19 being urged in one direction by a spring 23 to move the stud 21 into engagement with the cam.

A separate hammer 24 is carried on a spring arm 25 which extends from a lever 26 and rests against the stop member 25—a. The said lever 26 is pivotally mounted on a stud 27 which extends from the supporting plate 5 into the bell member 12. The said lever 26 carries a stud 28 which also engages the cam 15 and a spring 29 urges said lever in one direction to move the stud 28 into engagement with the cam.

In the embodiment of the invention illustrated, a suitable bracket 30 may be secured to the supporting plate 5 for fastening the bell to such as the handle bars of a bicycle.

25 In the form above described the bell member 10 is preferably of a different tone than the bell member 12, and the operation of the bell is as follows:

When it is desired to ring the bell, the bell member 12 is rotated upon the shaft 6 by simply giving it a spin with the fingers. This will cause the bell to spin on said shaft 6 and rotate the cam 15 therewith. The projections 16 of said cam will then engage with the studs 21 and 28 and cause the levers 19 and 26 to oscillate on their respective studs 20 and 22, under the influence of the springs 23 and 29. This will cause the hammers 17 and 24 to vibrate and repeatedly strike their respective bell members 10 and 12 and thereby produce a double tone. It will be clearly understood that the spinning action of the bell member 12 is caused by either imparting a succession of tangential blows to the bell member with the fingers, if a continuous sound is desired, or by grasping the said bell member with the fingers and giving it a sudden twirl if a short ringing is desired. Due to the fact that the bell member 12 is of a relatively large mass, and is required to turn a cam of a small radius against the light spring tension of the springs 23 and 29, the inertia of the member 12 will cause it to rotate several revolutions between the times that the fingers have been removed therefrom and the friction of the associated parts causes the bell member to stop rotating.

As shown, the studs 21 and 28 are also disposed in such relation to the cam 16 that the levers 19 and 26 will be rocked successively to thereby permit the two bells to be struck at different times so that the two-toned effect may thereby be sounded more clearly.

In the modified form illustrated in Figs. 4 and 5, my invention is embodied in a bell having a single bell member 31 which is rotatable on a shaft 32 which extends from the supporting plate 5—a. In this form, a lever 33 is pivotally carried on a stud 34 which also extends from the supporting plate 5—a, and the said lever is urged in one direction by a spring 35 to retain an extension member 36 in contact with a suitable cam 37. When said cam is caused to rotate by a twisting of the bell member 31, the hammer 38 which is carried on a spring arm 39 oscillates and its motion is restricted by a stop stud 40.

I claim:

1. A bell comprising a supporting plate, a stationary shaft extending perpendicularly from said plate, a bell member rotatable on said shaft, a lever pivotally carried on said plate, a resilient extension on said lever, a striker carried by said extension for striking said bell member stud on said lever, and cam means rotatable with said bell member and engageable with said stud for oscillating said lever to cause operation of the striker.

2. A bell comprising a supporting plate, a stationary shaft extending through said plate and projecting perpendicularly from opposite sides thereof, a stationary bell member carried by said shaft at one side of said supporting plate, a striker for said stationary bell member, a rotatable bell member rotatably carried upon said shaft at the opposite side of said supporting plate, a striker for said rotatable bell member, means for actuating said strikers carried by said rotatable bell, an operative connection between said strikers and said actuating means to cause operation of the strikers upon rotation of the rotatable bell, and means for repositioning said strikers relatively to said actuating means after striking the bells.

3. A bell comprising a supporting plate, a shaft rigidly mounted in said plate and extending perpendicularly thereto from the opposite sides of the plate, a stationary bell member carried upon said shaft at one side of said supporting plate, a lever pivotally carried on said plate within said stationary bell member and having an extension thereon projecting to the opposite side of said plate, a striker carried by said lever for striking said stationary bell member, a rotatable bell member carried upon said shaft at the opposite side of said supporting plate, a lever pivotally carried on said supporting plate within said rotatable bell member and having an extension thereon, a striker carried by said last named le-

ver for said rotatable bell member, cam means carried by said rotatable bell member and engageable by said extensions; said cam means being adapted to actuate said extensions upon rotation of the rotatable bell member and thereby oscillate said levers and strikers to cause each of the said strikers to deliver an impact to its respective bell member, and means for repositioning said levers after each operation thereof.

10 4. A bell comprising a supporting plate, a shaft extending through said plate and projecting perpendicularly from opposite sides thereof, a stationary bell member carried by said shaft at one side of said supporting plate, a striker for said stationary bell member pivotally mounted on said plate within said stationary member, a bell member rotatably carried upon said shaft at the opposite side of said supporting plate, a striker for said rotatable bell member pivotally mounted on said plate within said rotatable bell member, cam means rendered operable upon rotation of the rotatable bell member, means on each of said strikers operable by said cam means for causing operation of the strikers to successively strike said bell member on rotation of said cam means and spring means for yieldingly retaining said operable means in position to be engaged by said cam means.

30 5. A bell comprising a supporting plate, a shaft extending through said plate and projecting perpendicularly from opposite sides thereof, a bell carried on said shaft at each side of said plate; one of said bells being rotatable upon the shaft, cam means carried by said rotatable bell, a first 35 striker pivotally mounted upon said plate, a stud on said striker in engagement with said cam means and operable thereby to cause said striker to strike said rotatable bell, a second striker mounted upon the opposite side of said plate to strike the other bell, a stud on said second striker extending through said plate into engagement with said cam and operable by said cam to cause the second striker to strike the rotatable bell; each of said strikers having means for returning it to normal position after each impact against the bell.
